PORTABLE COOK STOVE, OR THE LIKE

Herman K. Busse, 3201 Palos Verdes Drive N.,
Palos Verdes Estates, Calif.

Filed Feb. 11, 1964, Ser. No. 78,593

Term of patent 14 years

(Cl. D81—10)

FIG. 1 is a perspective view showing the top and one side of a portable cook stove, or the like, embodying my new design;

FIG. 2 is a perspective view showing the bottom and opposite side thereof; and

FIG. 3 is a top plan view thereof.

I claim:

The ornamental design for a portable cook stove, or the like, as shown.
